UNITED STATES PATENT OFFICE.

JOSEPH H. BRICKWORTH, OF ST. LOUIS, MISSOURI

MECHANISM FOR AERIAL NAVIGATION.

1,072,078

Specification of Letters Patent.

Patented Sept. 2, 1913.

Application filed October 12, 1908, Serial No. 437,385. Renewed May 21, 1913. Serial No. 769,094.

To all whom it may concern:

Be it known that I, Joseph H. Brickworth, a citizen of the United States, residing at St. Louis, Missouri, have invented a new and useful Mechanism for Aerial Navigation, of which the following is a specification.

This invention has reference to aerial navigation, and more particularly to that type of mechanism for aerial navigation which is heavier than the air supporting it, and which is raised and supported and then propelled by the operation against the air of the driven mechanism.

15 The object of the invention is to produce, in connection with a suitable frame and propelling mechanism mounted thereon, supporting and lifting mechanism comprising a number of devices of the screw-propeller type arranged to operate in horizontal planes whereby the entire mechanism may be raised to and sustained at any desired altitude in the air, in combination with a number of devices, whose function generally is that of 20 a parachute, which coöperate with the supporting and lifting mechanism to balance the machine, and whereby sudden falling or collapse of the machine will be prevented, and by which the machine may, in any 25 instance, be lowered gently and safely to the earth.

In the accompanying drawings which form part of this specification, Figure 1 illustrates one embodiment of the invention. 35 Fig. 2 is a vertical sectional view of the upper end of one of the vertical shafts which carry the lifting and balancing devices. Fig. 3, is a similar sectional view of the lower end of one of said shafts. Fig. 4 is 40 a plan view of a part of one of the lifting devices.

The open frame work 1 is of any suitable construction adapted for these purposes. Said frame work supports, preferably near 45 the middle part thereof, a power or driving mechanism 2 which is arranged to rotate the shafts 3 extending toward the ends of the machine. One of said shafts carries a propeller 4 whereby the machine will be 50 driven through the air. To each of the shafts 3 a gear wheel 5 is attached, said gears being enmeshed with gears 6 on the lower ends of the hollow or tubular vertical shafts 7, thereby causing said shafts to be 55 rotated when the power mechanism is in

operation. At a convenient place on each of said shafts 7 a hub 8 is attached and a series of blades 9 extend radially from each of said hubs. The blades 9 are in oblique planes, their leading edges being highest so that when the shafts 7 are rapidly rotated the machine will be lifted in to the air and, by operation of the propeller 4, driven forwardly. Above the blades 9 on each shaft 7 is a device 10, conforming in shape generally to that of a parachute, and subserving a like function in lowering the machine to the earth. The devices 10 are composed of sections of suitable fabric having their outer or lower edges secured to rings 11. Braces 70 or reinforcements 12 may be utilized to strengthen and hold the rings 11 in proper position, said braces having their inner ends secured to flanged collars 13 on the shafts 7. Tie rods or cables 14 connecting revolving 75 caps 15 on the upper ends of the shafts 7 together and with other parts of the machine brace and strengthen the structure. The shafts 7 are tubular and have holes 16 above the blades 9 for admision of air under the parts 10.

It will be observed that the devices 10 are arranged above the heavier frame work and, therefore, act as balances to prevent overturning of the machine, and also are 85 safeguards against rapid falling or collapse of the machine. Being in constant rotation when in use they offer less resistance to forward propulsion of the machine.

I am aware that there may be variations 90 in the structure, particularly in the arrangement of the component parts of the machine, without in the least departing from the spirit and scope of the invention. I do not restrict myself to such identical structure and arrangement, but

What I claim and desire to secure by Letters Patent is—

1. In a machine of the character described, the combination with a frame work, vertical hollow shafts supported by said frame work, a lifting propeller on each of said vertical shafts, a parachute on each of said shafts above said lifting propellers, said shafts having openings above and below 100 said propellers effectively to conduct air from above said propellers to the under side thereof, and braces holding said vertical shafts from becoming displaced, of power mechanism, of a plurality of shafts 105 110

driven by said power mechanism, a driving propeller on one of said shafts, and gears entraining said last-named shafts with said vertical shafts whereby said lifting propellers and said parachutes will be driven when said driving propeller is operated, substantially as specified.

2. Mechanism of the character described comprising a frame work, power mechanism on said frame work, a number of vertical hollow shafts rotated by said power mechanism, an open parachute on each of said shafts, and a lifting propeller on each shaft below the parachute thereon, said shafts having openings above and below said propellers effectively to conduct air from above said propellers to the under sides thereof, substantially as specified.

3. A machine of the character described

comprising a frame work, a number of vertical hollow rotating shafts, a permanently operable lifting propeller on each shaft, a number of permanently open parachutes above said propellers and above said frame work, said shafts having openings above and below said propellers effectively to conduct air from above said propellers to the under side thereof, a driving propeller, and power mechanism for operating said lifting propellers, said parachutes, and said driving propeller, substantially as specified.

In testimony whereof I hereunto affix my signature this 9th day of September, 1908, in the presence of two witnesses.

JOSEPH H. BECKWITH. [L.S.]
